UNITED STATES PATENT OFFICE.

MATTHIAS S. YEAGER, OF LOS ANGELES, CALIFORNIA, ASSIGNOR TO LIBERTY BURNER CO., A CORPORATION OF CALIFORNIA.

GAS-BURNER.

1,296,581.

Specification of Letters Patent.

Patented Mar. 4, 1919.

Application filed February 7, 1918. Serial No. 215,734.

To all whom it may concern:

Be it known that I, MATTHIAS S. YEAGER, a citizen of the United States, residing at Los Angeles, county of Los Angeles, and 5 State of California, have invented new and useful Improvements in Gas-Burners, of which the following is a specification.

My invention has relation more specifically to a gas burner used in combination 10 with a generator.

In gas generators having burners attached thereto, of the type best illustrated in U. S. Patent 1,238,003, to T. J. Crook, dated August 21, 1917, entitled "Hydrocarbon-burner," the flame delivery means consists of a plurality of slotted burner walls communicating with a gas chamber. The slotted burner walls in the above construction are vertically disposed in parallel relation to 15 each other, and as a consequence the gas flames issuing therefrom are drawn upwardly by the draft of the stove or the casting in which the generator burner is located, the flames "hugging" the slotted surface of 20 the burner wall, thereby causing oxidation of the upper portions of the burner slots, and greatly impairing the efficiency of the burner. The oxidation or fusing together of the upper portion of the burner slots is even 25 more noticeable when the flow of gas through the slots is comparatively small, the flames closely "hugging" the burner walls, and accomplishing the oxidation of the slots much more quickly than if the gas were under 30 greater pressure.

By disposing the slotted burner walls in divergent relations to each other as in my construction, the above recited difficulties resulting from oxidation of the burner slots is 35 practically eliminated, the flames when issuing therefrom, being directed upwardly and away from the burner walls.

It is an object of my invention to provide a burner construction in which the slotted 40 burner walls are so disposed that oxidation of the burner slots is avoided.

Another object of my invention is to provide burner construction in which the slotted burner plates are removable when for any 45 cause they may require replacement.

I accomplish the above objects by means of the burner described herein and illustrated in the accompanying drawing in which:

Figure 1 is a side elevation of my improved burner construction.

Fig. 2 is a transverse section through my burner taken on line 2—2 of Fig. 1, looking in the direction indicated by the arrows thereon.

Referring more specifically to the drawings 5 designates the burner's supporting legs which are secured in the fire box of the stove or similar structure in any well known manner. Secured by means of screws 6 to the 65 burner legs 5 is an elongated burner head 7 preferably formed from cast iron, and consisting of bottom wall 8, side walls 9, top wall 10, and end walls 11. A longitudinally extending recess 12 is formed in the interior 70 of the burner head by means of side walls 13, top wall 14, and end walls 11 and 11'. The walls of the structure heretofore described form a gas chamber 15, the said chamber having an inlet 16 leading thereto at one end 75 thereof. Secured in inlet 16 in any suitable manner is a gas delivery pipe 17 which extends upwardly and terminates in a gas mixing chamber 18 of any approved form. The mixing chamber 18 is provided with an air 80 inlet port 19 adapted to be closed by a removable cover or plug 20 to regulate the quantity of air delivered to the mixing chamber. Secured to the burner body adjacent 85 the top thereof by means of an upwardly extending bracket 21 is a gas generator 22, preferably of cylindrical form and extending parallel with the top of the burner casting and slightly above the same, as clearly 90 illustrated in Fig. 1 of the drawing. The 95 end of generator 22 terminates within the mixing chamber 18, and its inlet 23 is connected to a source of fuel supply such as a tank (not shown). The above description of the generator which is connected to my 95 approved burner construction will be sufficient as it bears no relation to the novel features of my burner, and it is only described to show its connection therewith.

The upper wall 10 of the burner head is 100 provided with a plurality of transversely disposed burner slots 25 adapted to deliver flames against the gas generator 22 when the burner is in operation.

Disposed along the longitudinally extending edges of wall 10 are recesses 26 in which are disposed in any suitable manner, wicks 27 preferably formed from asbestos, and de-

signed to be used in starting the generator when the burner is put into operation.

The side walls 9 of the burner head preferably extend in a downwardly and outwardly divergent relation to each other, as clearly shown in Fig. 2 of the drawing. Each of side walls 9 are preferably provided with a pair of longitudinally extending seats 28 adapted to receive burner plates 29, each 10 plate being provided with a plurality of vertically disposed burner slots 30. The burner plates 29 are held in gas tight relation in the recesses 28 in any suitable manner, preferably by means of fire clay or asbestos packing, not shown.

By disposing burner plates on the side walls of the burner head in an inclined relation to each other, the flames issuing therefrom will be directed upwardly by the draft 20 of the stove in which the burner is mounted, and the lower portion of the flames will not contact or "hug" the upper slotted walls of the burner plates so as to cause oxidation of the slots, and thus impair the efficiency of 25 the burner.

Also it will be noted from the above description that when the flames issuing from the slotted burner plates are turned down by means of the burner regulating valve (not shown) that the lowermost portions of the flames will not be directed against the upper portion of the burner slots to cause oxidation or fusing together, as the inclined side walls

would direct the flames upwardly and away from the slots.

It will be apparent from the above that I have provided a burner in which the burner plates will not have to be renewed very frequently, and have obviated by such a construction a serious difficulty that has been 40 experienced with burners of the type heretofore mentioned.

What I claim is:

1. A gas burner construction, comprising a hollow burner head having a gas inlet 45 leading thereto and being provided with downwardly and outwardly divergent side walls, each of said walls having longitudinally extending openings formed therein, and a pair of burner plates having vertically 50 disposed slots therein adapted to seat in said openings.

2. A gas burner head having a gas inlet leading thereto and being provided with downwardly and outwardly divergent side 55 walls, each of said walls having a longitudinally extending slot formed therein, the upper and lower edges of said slots being provided with seats, and a slotted burner plate having vertically disposed slots therein, 60 slidably mounted in the seats formed on the edges of each of said openings.

In witness that I claim the foregoing I have hereunto subscribed my name this 17th day of January, 1918.

MATTHIAS S. YEAGER.
